UNITED STATES PATENT OFFICE.

CHARLES W. KINCAID, OF DALLAS, TEXAS, ASSIGNOR TO GILBERT & BARKER
MANUFACTURING COMPANY, OF WEST SPRINGFIELD, MASSACHUSETTS, A
CORPORATION OF MASSACHUSETTS.

FLUID-DISPENSING APPARATUS.

1,305,289.

Specification of Letters Patent. Patented June 3, 1919.

Application filed November 11, 1918. Serial No. 261,964.

To all whom it may concern:

Be it known that I, CHAS. W. KINCAID, a citizen of the United States, residing at Dallas, in the county of Dallas and State of Texas, have invented certain new and useful Improvements in Fluid-Dispensing Apparatus, of which the following is a specification.

My invention has relation to an improvement in oil or similar fluid dispensing apparatus, and in such connection it relates more particularly to a device for receiving the drip from the dispensing faucet and conducting the same to the reservoir.

In apparatus for dispensing oil or suitable fluids from a faucet beneath which a receiving vessel is placed and withdrawn considerable loss and inconvenience has arisen due to the fact that after the faucet is shut off and the vessel withdrawn, the drip from the faucet falls to the ground or to the exterior of the fluid reservoir. It is true that careful employees minimize this loss by permitting the receiving vessel to remain under the faucet until the drip has ceased. But this necessitates loss of time in dispensing the fluid and does not wholly take care of belated dripping from the faucet. If in an attempt to cure this defect, the reservoir is provided with a drip cup leading directly to the interior of the reservoir, such cup must of necessity be directly under and quite some distance below the faucet and of enlarged area to catch the drip. Such a drip cup permits entrance of dirt or grit to the reservoir when the cup is not covered by the receiving vessel.

The main object of my invention is to provide a means for catching the drip, which means is normally automatically maintained directly under the faucet and incloses the discharge outlet or spout of said faucet, but can be swung away from said spout when the receiving vessel is placed under the spout, the drip catching means swinging back to normal position as the receiving vessel is removed.

In the preferred embodiment of my invention, a stand pipe is erected on the reservoir adjacent to the dispensing pipe, and is arranged to support a drip pipe telescoping in the stand pipe and carrying a branch or arm so curved or shaped as to fit directly under the discharge spout of the faucet on

the dispensing pipe. The drip pipe is provided with means preferably two pins co-acting with the top of the stand pipe to support the drip pipe in the stand pipe and to normally swing the drip pipe with its branch normally under the faucet. 55 60

The branch or arm is cut away to receive and inclose the faucet spout. The top of the stand pipe is provided with cam like slots to receive the pins of the drip pipe, said pins riding by gravity down in said 65 slots to swing the pipe toward the faucet.

The nature and scope of my invention will be more fully understood from the following description, taken in connection with the accompanying drawings forming part 70 hereof, in which—

Figure 1 is a perspective view of an oil dispensing apparatus provided with a drip receiving means embodying the main features of my invention. 75

Fig. 2 is a detail view enlarged of the stand pipe and drip pipe and of the means for supporting the drip pipe on and within the stand pipe.

Fig. 3 is a top or plan view of Fig. 2, 80 and

Fig. 4 is a detail of the upper end of the drip pipe.

Referring to the drawings, 1 represents the fluid reservoir, 2 the dispensing pipe, 3 the dispensing faucet and 4 the measuring device, all of well known construction and arrangement. The pipe 2 and its accessories are supported on a plate 5 at the top of the reservoir and this plate 5 is 90 tapped to receive a stand pipe 6.

The top edge or rim of the pipe 6 is cut away to form two oppositely disposed cam slots 7. The stand pipe 6 is traversed by a drip pipe 8 telescoping in pipe 6 and extending some distance below the same into reservoir 1. The drip pipe 8 has two diametrically oppositely disposed pins or lugs 9 each arranged to ride in a slot 7 of stand pipe 6. The slotted rim of pipe 6 and the pins 9 of pipe 8 are so arranged as to coact in forcing the pipe 8 as it rides up or down in the pipe 6. The drip pipe 8 is provided with a branch 10 terminating in an upwardly extended portion 11. This end portion of branch 10 is cut away as at 12 to slide past and surround the discharge orifice 13 of faucet 3. The cut-away portion

12 of the upper end of branch 10 may be provided with a lip 14 to assist in receiving the drip from faucet 3.

The pipe 8 with its branch 10 is normally 5 swung toward the faucet so that its cut-away upper end incloses the discharge orifice 13 of said faucet. When, however, a receiving vessel is pushed under said faucet, the pipe 8 and its branch are forced away from the 10 faucet, returning, however, under gravity when the vessel or can is withdrawn from the faucet.

The pins 9 may be covered with antifriction washers or even rollers if desired to 15 insure free movement of the pins in the cam slots. Various modifications in arrangement and construction of this swing joint may be readily devised without departing from the spirit of my invention.

Having thus described the nature and objects of my invention, what I claim as new and desire to secure by Letters Patent, is—

1. In combination with a reservoir and a dispensing faucet, a means for catching the drip from the faucet and conveying the drip to the reservoir, said means supported to 25 swing by gravity under the faucet to in-

close the same when the receiving vessel is withdrawn from the faucet.

2. A drip collecting attachment for fluid 30 dispensing apparatus, comprising a stand pipe located near the dispensing faucet, a drip pipe mounted to swing on the upper rim of the stand pipe, said drip pipe telescoping in the stand pipe, and a branch extending 35 from the drip pipe and constituting a drip receiving cup, combined with means on the drip pipe coating with means on the upper rim of the stand pipe whereby the drip pipe and branch are swung by gravity beneath the faucet, when the faucet is not in use.

3. In a device of the character described, a stand pipe, two diametrically opposite cam slots cut into the upper rim of the stand 40 pipe, a drip pipe extending through the stand pipe, and pins on the drip pipe arranged to ride in the cam slots of the stand pipe, said pins and cam slots constituting a means for supporting the drip pipe and for swinging 45 the same on the stand pipe.

In testimony whereof I have signed my name to this specification.

CHARLES W. KINCAID.
